FOLDING BOX

Arthur W. Lovejoy, Lowell, Mass.

Application January 28, 1937, Serial No. 122,736
Renewed April 11, 1939

1 Claim. (Cl. 229—16)

My invention relates to a receptacle and a blank therefor and more especially to a receptacle or box formed out of a blank of sheet material, such as paper or cardboard, and folded to 5 form side walls which are secured to one another and to the receptacle bottom at one or more of the marginal edges or sides of the latter.

In receptacles, formed out of blanks of cardboard or the like, as heretofore known, it has 10 been the practice either to join the side wall sections in groups to certain of the side edges of the receptacle base, as exemplified by the patent to G. O. Crawford, November 17, 1908, Patent Number 904,050, or to join each side wall section individually to the base, as exemplified in the patent 15 to Charles A. Scotcher, June 10, 1924, Patent Number 1,497,661. When the side wall sections are individually joined to the base it is required that some means be provided for securing each 20 side wall section to its neighbors, while in the case of receptacles formed out of blanks, in which the side wall sections are joined in groups to single edge portions of the base, there is lacking any support for the base along its remaining 25 edge portions, and the latter, especially if two of its adjacent edge portions are unsupported, is apt to sag at these points or to permit unsightly gaps to open up between the base and side walls through which, in some instances, the material 30 carried in the receptacle may escape.

One of the principal objects of the present invention is to bring about a form of receptacle formed out of a blank of sheet material in which the side walls and base are more rigidly and efficiently joined together against relative movement than has heretofore been possible.

A further and more specific object of the invention is to bring about a form of receptacle of the above character, in which all portions of the base are supported against sagging and in which 40 it is impossible for gaps to form between the side walls and base through which material carried in the receptacle may pass.

To these and other ends, the invention consists in the novel features and combinations of parts to be hereinafter described and claimed.

In the drawing:

Fig. 1 is a plan view of a blank from which one form of receptacle according to the invention 50 may be formed;

Fig. 2 is an elevational view of the receptacle formed from the blank of Fig. 1;

Fig. 3 is a partial plan view on an enlarged scale of a receptacle formed from the blank of 55 Fig. 1;

Fig. 4 is a plan view of another form of blank from which a receptacle may be made, and

Fig. 5 is a plan view of a receptacle formed out of the blank shown in Fig. 4.

Referring now to the drawing, in which I 5 have illustrated my invention by showing preferred embodiments of the same, and with special reference at present to that form of the invention shown in Figs. 1, 2 and 3, the reference numeral 10 indicates in general a blank from 10 which a receptacle may be formed and which blank is composed of a single piece of suitable sheet material such as cardboard, paper or the like.

The blank 10 comprises, in this instance, a 15 hexagonal portion 11, which in the completed receptacle will form the base or bottom, and wings 12 and 13, which form the receptacle side walls. Preferably the wings 12 and 13 are joined to the base portion 11 at the opposite sides 14 20 and 15, of the latter, the wings corresponding generally in size and shape. The wing 12, comprises three sections 16, 17 and 18, section 17 being joined to the base 11 at the marginal edge portion or side, the latter being defined by a 25 scored line in the blank. The section 16 joins the section 17 at one of the side edges of the latter, formed by the scored line 19, while the section 18 joins the section 17 at the other side edge thereof, formed by the scored line 20. It will be 30 noted that scored lines 19 and 20 taper outwardly away from one another so that the section 17 is keystone shaped. In similar manner the section 21, of wing 13, is joined to base 11 along a scored line forming the edge 15 of the base, 35 the section 22 joining the section 21 at one of the side edges of the latter, formed by the scored line 23, while the section 24 joins the section 21 at the other side edge of the latter, formed by the scored line 25. The side wall sections, in this 40 instance, correspond in number to the sides of the base 11 and are identical in shape and size.

The blank is scored at 26, 27, 28 and 29 to form the remaining sides of the bottom, and attached to the bottom at these sides or edge portions are 45 generally triangular tabs 30, 31, 32 and 33, the blank being slit along the lines 34, 35, 36 and 37 to separate the tabs from the adjacent side wall sections. It will be noted that the tabs 30 and 31 are provided with adjacent free edges 38 and 39 50 which are at an angle to one another, the angular relation of these edges varying according to the degree of taper provided in the side walls of the assembled receptacle, as will be herein-after pointed out. In similar manner the ad- 55

- adjacent free edges 40 and 41 of tabs 33 and 32 are at an angle to one another, the angles formed between the tab edges in both instances opening outwardly.
- 5 The blank is formed into an open ended receptacle such as is shown in Figs. 2 and 3 by erecting, folding around the octagonal base 11 and fastening together the various side wall forming elements of the blank. Thus, the tabs 30, 31, 32 and 33 are folded upwardly about the scored lines 26, 27, 28 and 29 and the wings 12 and 13 folded upwardly about the scored lines 14 and 15. The wings are then folded along the scored lines 19, 20, 23 and 25 to bring the lower edges of the sections into contact with the bottom 11 about its entire periphery, the tabs 30, 31, 32 and 33 being on the interior of the receptacle thus formed. For the purpose of securing the receptacle in its assembled form, end sections 42 and 43 are provided on the opposite ends of wings 13, end section 42 being attached to section 22 along scored line 44, while end section 43 is attached to section 24 along scored line 45. When the receptacle is erected the sections 42 and 43 overlap sections 16 and 18 and are attached thereto by adhesive or, if preferred, by locking tongues 46 and 47 which are passed through the slits 48 and 49 in sections 16 and 18. The angle between the edges 38 and 39, of tabs 30 and 31, is such that when the receptacle is erected, as described above, the tab 30 fits flatly against the inner surface of section 22, while the tab 31 fits flatly against the inner surface of section 16, the angle between the tab edges 38 and 39 being such that these edges abut in the corner of the receptacle formed between sections 16 and 22, as shown in Fig. 3. The tabs 32 and 33 fit in the corner formed by sections 18 and 24, the edges 40 and 41 abutting in similar manner.
- 40 Preferably receptacles in accordance with the invention are made with tapering side walls, thus in the present instance the keystone shape given to the sections of the side walls of the receptacle cause the latter to taper downwardly, the upper end of the receptacle being somewhat larger than the bottom, as shown in Figs. 2 and 3. The taper given to the side walls of the receptacle is of added advantage in supporting the bottom along the free edges 26, 27, 28 and 29. It will be apparent that any downward movement of the base at the edges 26 and 27 will cause a wedging movement of tab 30 towards tab 31 which wedging movement is opposed by the contact of edge 38 with edge 39. Furthermore, even if the side walls of the receptacle did not have the taper provided in the preferred form, any bending of the bottom in a downward direction, in that portion of the bottom included between the bottom edges 26 and 27, would cause the upper ends 60 of the tabs to be forced against and into the corner of the receptacle and would be opposed by the contact of one tab with the other.

In Figs. 4 and 5 there is shown another form which the invention may take. In this embodiment the base 50 is generally triangular and provided with sides 51, 52 and 53 formed by scored lines in the blank. A wing, generally designated 5 by the reference numeral 54, joins a base 50 along the side defined by the scored line 51, wing 54 being provided with sections 55, 56 and 57 which may be folded to circumscribe the base about its contour. Tabs 58 and 59 are joined to 10 base 50 along the sides 52 and 53 respectively, the tabs being provided with free edges 60 and 61 which abut in the erected receptacle to support those portions of the base included between the sides 52 and 53 as shown in Fig. 5. In this 15 instance it would be apparent that, except for the support given to the base by the cooperation of the tabs with one another and with the side walls of the receptacle, the base would be free to swing downwardly about the side 51. 20

If preferred, the upper ends of the side wall sections of the receptacle shown in the several figures of the drawings may be provided with scallops, as for example 62 in Figs. 1, 2 and 3, and 63 in Figs. 4 and 5, the scalloped portions 25 joining the side wall sections along scored lines, as at 64 and 65. In Fig. 5 one of the scallops 63 is shown folded downwardly over the open upper end of the receptacle, and it will be readily understood that the remaining scalloped portions 30 may likewise be folded down to partially close the upper end of the receptacle.

While I have shown and described a preferred form of the invention, it will be readily understood that it is not to be limited to the details 35 shown, but is capable of modification and variation within the spirit of the invention and the scope of the appended claim.

What I claim is:

A receptacle formed out of a single piece of sheet material, the blank of material being 40 scored to form a hexagonal base, wings attached one to each of two of the opposite scored sides of the base, each wing comprising a central section of keystone shape attached directly to the base, side sections attached at their sides by 45 scored lines one at each of the sides of the central sections, all of said sections being of uniform size and shape and being provided with side edges which taper outwardly away from one another, and triangular tabs formed on the remaining sides of the base, the tabs being so shaped as to fit into the corners formed between the adjacent upwardly and outwardly tapering side walls when the receptacle is erected, the adjacent tabs resting on the side walls and abutting one another to prevent downward sagging of the base, and means for attaching the adjacent side edges of the wings to one another when the receptacle is erected.
